DUAL FUNCTION FUZES

Arthur M. Lohmann, Hopkins, Minn., assignor to Honeywell Inc., Minneapolis, Minn., a corporation of Delaware

Filed July 10, 1964, Ser. No. 381,725
9 Claims. (Cl. 102—74)

This invention relates generally to a munition fuze having both delay and instantaneous detonating modes, and more particularly relates to a dual function fuze for use in a bomb dropped from a low flying aircraft, to prevent damage to the aircraft from the bomb explosion.

With the advent of highly accurate radar controlled antiaircraft artillery systems, it has become increasingly more dangerous for aircraft to bomb from high altitudes.

It has become imperative, especially in the combat area itself, to perform the bombing run at extremely low altitudes, both for accuracy reasons and for safety reasons.

A dangerous situation arises when a high speed aircraft flying at extremely low altitudes drops a high yield conventional weapon. The bomb after release tends to travel along with the aircraft at the same speed until it impacts with the ground. It can be seen that at these low altitudes, the bomb might well burst directly under the very aircraft that released the bomb. The present fuzing system is designed to prevent damage to the aircraft during a low altitude bombing run.

Although the delay detonating feature that allows the aircraft to escape the vicinity before detonation is important when the bomb is delivered at low altitudes, it is not a desirable feature where the bomb is dropped from a conventional high altitude position. This invention provides maximum effectiveness under all conditions, consistent with safety, by providing instantaneous detonation if the bomb is dropped above a certain altitude but allowing a delay period between impact and detonation if the bomb is dropped from below the safe altitude. These dual functions are automatically performed. No manual input or other externally supplied signal is required.

In the present fuze, a delay detonator and an instantaneous detonator are carried by a rotor or carrier member. Under normal conditions, both detonators are out of line with a firing pin. Upon launch (first event) of the munition, the rotor is moved from the safe position to a second position with the delay detonator in line with the firing pin. The rotor is held in the second position for a period of time that is of sufficient duration for the aircraft to escape the area before detonation occurs. If impact (second event) occurs during the time that the rotor is in the second position, the munition will detonate after a period of time determined by the delay detonator. After the delay period has occurred without impact, the rotor is moved from the second position to a third instantaneous detonating position with the instantaneous detonator in line with the firing pin. If impact occurs with the rotor in the third position, the munition will explode immediately.

It therefore can be seen that if the bomb is dropped from below a safe altitude, the delay detonator will be in line with the firing pin when impact occurs. The delay detonator will not explode until the aircraft has had time to escape the area. If, however, the bomb is dropped from above the safe altitude, the rotor will have reached the third position and detonation will occur immediately upon impact.

It is therefore a primary purpose of the present invention to provide an automatically operated dual function munition fuze.

Another object of the present invention is to provide both delay and instantaneous operating modes in a muni-

2

tion fuze that will prevent instantaneous detonation of the bomb until a predetermined time has elapsed after launch.

Another object of the present invention is to provide a munition fuze that will delay detonation of a bomb dropped from below a safe altitude and will allow instantaneous detonation of a bomb dropped from above the safe altitude.

Other objects of this invention will be apparent from the specification and claims when considered in connection with the accompanying drawings, in which:

FIGURE 1 is a top plan view of the fuze with the rotor in the safe position;

FIGURE 2 is a top plan view of the fuze with the rotor in a second or delay detonating position;

FIGURE 3 is a top plan view of the fuze with the rotor in a third or instantaneous detonating position; and

FIGURE 4 is an isometric view of the fuze.

Referring now to the drawings, there is disclosed in FIGURE 1 a munition fuze having a housing 10 of generally circular cross section. Rotatably mounted within housing 10 on an axis 12 is a rotor or carrier member 14. Motive power for driving rotor 14 about axis 12 is provided by a spiral drive spring 16 that is connected to housing 10 by a pin 18 and to rotor 14 by a pin 20.

As disclosed in FIGURE 4, rotor 14 is a right cylindrical section having a top surface, a parallel bottom surface, and a peripheral edge connecting the two surfaces. Extending from the edge of rotor 14 is a lug or stop member 22. Extending from the inner surface of housing 10 is a corresponding stop member 24 that lies in line with lug 22 to prevent rotation of rotor 14 beyond a certain point as disclosed in FIGURE 3.

The fuze is to be mounted in a projectile or bomb so that the top section as disclosed in FIGURES 1-3 would lie perpendicular to the longitudinal axis of the projectile. Arrow 26 in FIGURE 4 discloses the direction of flight of the projectile in which the subject fuze is mounted.

A flat spring member 28 is mounted within housing 10 to lie parallel to the upper surface of rotor 14. Spring member 28 is connected at one end to housing 10 and is normally biased to the position disclosed in FIGURE 4. Mounted on the lower surface of spring member 28 are a pair of hooked or barbed firing pins 30 and 32 and a stop pin 34. As shown in phantom in FIGURE 1, stop pin 34 lies in line with lug 22 with rotor 14 in the safe position to prevent movement of the rotor. Spring member 28 is flexible and is movable from the position shown in FIGURE 4 to a position in which the lower surface lies directly against the upper surface of rotor 14.

Formed within the upper surface of rotor 14 are a pair of short annular grooves 36 and 38. Both grooves are of sufficient length to accommodate both firing pins. Mounted within groove 38 is a coil spring 40, the purpose of which is to engage and lock the barbed firing pins if spring member 28 is forced against the top surface of rotor 14 when either one or both of the firing pins are in line with groove 38. The purpose for and the full correlation between the hooked firing pins and the coiled spring mounted in groove 38 are fully explained in my copending application Serial No. 291,894, filed July 1, 1963, now Patent No. 3,157,125.

Also mounted in the upper surface of rotor 14 is a delay detonator 42, an open cup 44, and an instantaneous detonator 46. Delay detonator 42 will provide a set time delay between the time it is struck by a firing pin and the time it explodes. Detonator 46 will explode immediately upon being struck by a firing pin.

Mounted in the upper portion of housing 10 above flexible member 28 is a launch and impact sensing device 48 (shown schematically). Although device 48 is essential for operation of the fuze, the specific structure is

only of incidental importance and is thus not disclosed in detail. The same structure as that disclosed in my previously mentioned copending application could be utilized. To detect launch of the munition for example, a bore riding safety pin could be used. The principle of a bore riding safety pin is explained in the Woodberry Patent 2,118,062 that issued May 24, 1938. Setback operated devices could also be utilized to detect launch, and in the case of rotating munitions, a centrifugally operated mechanism could be used. The Woodberry patent also discloses means for detecting impact that could be utilized in this invention. Various other devices are available in the fusing art for detecting a first event (in this case launch) and a second event (in this case impact).

Formed on a portion of the periphery of rotor 14 adjacent the lower surface thereof is a gear segment 50. Mounted adjacent rotor 14 in housing 10 is a corresponding gear wheel 52. Gear wheel 52 meshes with gear segment 50 to regulate the speed of rotation of rotor 14.

Gear wheel 52 is mounted on a shaft 54 and is driven by a helical torque spring 56. It is noted that rotor 14 is driven by spring 16 while gear wheel 52 is driven by spring 56. A second gear wheel 58 is concentrically mounted with respect to wheel 52 on shaft 54. A standard escapement mechanism 60 as disclosed in FIGURE 1 coacts with gear wheel 58 to regulate the speed of rotation of gear wheel 52 about shaft 54.

Concentrically mounted on top of gear wheel 52 is a generally cylindrical cam member 62. Cam member 62 is of circular cross section and has an open top. Formed along a small arc of the upper edge of cam member 62 is a slot 64.

Mounted adjacent gear member 52 on a shaft 56 is a cam follower member 68. Follower member 68 is mounted for limited movement about shaft 66 and includes a first arm 70 and a second arm 72. The upper surface of follower member 68 is parallel with the upper surface of rotor 14, and shaft 66 is also parallel with axis 12.

In FIGURE 1 it can be seen that in a first position, first arm 70 lies adjacent the periphery of rotor 14. Second arm 72 lies adjacent the inner surface of cam member 62. Extending from the lower surface of second arm 72 is a pin 74 that rides the inner surface of cam member 62. As shown in FIGURE 1, the fact that pin 74 rides the inner surface of cam member 62 prevents counterclockwise movement of cam follower member 68 about shaft 66.

In FIGURE 2, there is disclosed a curved tip of first arm 70 that lies in line with lug 22 to hold the rotor in the position shown in FIGURE 2.

A coil spring 76, connected between cam follower member 68 and housing 10, provides a counterclockwise bias to cam follower member 68. In FIGURE 3, gear wheel 52 has been rotated by spring 56 to a position in which slot 64 lies in line with pin 74. With slot 64 in this position, coil spring 76 drives cam follower member 68 counterclockwise to a second position so that firm arm 70 releases lug 22.

Operation

Prior to launch the fuze is in the safe position shown in FIGURE 1. Rotor 14 is held in the safe position by stop pin 34 lying in the path of lug 22. Firing pins 30 and 32 also tend to hold the rotor in the safe position since they lie in groove 36. In some applications pin 34 might not be required since the firing pins could hold the rotor in the safe position by themselves. Pin 34 is thus an additional safety feature.

With rotor 14 in the safe position, the firing pins are out of line with detonator 42 and detonator 46. If the bomb is mishandled or dropped with the fuze in the safe position, no explosion will occur since the firing pin cannot contact either detonator, and the detonators are also out

line with a lead cup (not shown) that is mounted in housing 10 beneath rotor 14. Even if a detonator should fire with the rotor in the safe position, the explosion will not ignite the lead cup.

- 5 Upon launch or other first event, a bore riding safety pin or other device (not shown) is actuated to release flexible spring member 28. Member 28 then moves to the position shown in FIGURE 4, releasing rotor 14. Once spring member 28 is released, rotor 14 is free to rotate in a clockwise direction under the influence of drive spring 16. The speed at which rotor 14 moves is regulated by escapement member 60 since segmental gear 50 is meshed with gear wheel 52 during this initial period of rotation. The length of gear segment 50 and the characteristics of escapement system 60 determine the speed and duration of the retardation of rotor 14. After gear segment 50 passes through the teeth on gear wheel 52, rotor 14 snaps to the second or delay detonating position shown in FIGURE 2.
- 10 During the time that rotor 14 is moving from the safe position to the second position, groove 38 and coiled spring 40 lie beneath one or both of the barbed firing pins. If impact of the fuze should occur during this initial period, at least one of the firing pins will penetrate coiled spring 40 to dud the fuze. This safety feature is fully described in my previously mentioned copending application.

With the fuze in the second position as disclosed in FIGURE 2, an impact will cause the impact sensing device to drive flexible member 28 against rotor 14, thereby driving firing pin 30 into delay detonator 42. At the same time, firing pin 32 is driven into coiled spring 40 to lock the rotor in the second position. Delay detonator 42 will then initiate the lead cup (not shown) after a predetermined delay period.

30 Rotor 14 is held in the second position shown in FIGURE 2 by arm 70 which lies in line with lug 22. At this time, gear wheel 52 is no longer meshed with gear segment 50. Gear wheel 52 continues to rotate in a counterclockwise direction, however, under the influence of helical spring 56 at a rate determined by escapement mechanism 60. During this period, the inner surface of cam member 62 prevents cam follower member 68 from rotating in a counterclockwise direction since pin 74 lies against the inner surface. After a preset period of time, slot 64 rotates to a position in line with pin 74, at which time coil spring 76 drives cam follower member 68 in a counterclockwise direction to release rotor 14. Rotor 14 then snaps virtually instantaneously to the third or instantaneous detonating position disclosed in FIGURE 3.

40 In the third position, instantaneous detonator 46 is in line with firing pin 30, and cup 44 is in line with firing pin 32. When impact occurs, impact sensing device 48 will drive spring member 28 against rotor 14 to ignite detonator 46.

50 In the preferred embodiment of the fuze, a time delay of two seconds is provided between the time rotor 14 leaves the safe position and the time the second position is reached. This two second delay is provided by the interaction between gear segment 50 and gear wheel 52. If, during this time, the fuze impacts, a firing pin will lock in coiled spring 40 to dud the fuze.

55 After two seconds, rotor 14 reaches the second position shown in FIGURE 2. Rotor 14 is maintained in this position for 3.5 seconds by first leg 70 of cam follower member 68. An impact occurring between two seconds and 5.5 seconds after launch will thus drive firing pin 30 into delay detonator 42. Delay detonator 42 provides an eight second delay between impact and explosion. At this point firing pin 32 is locked in coiled spring 40 so that subsequent bouncing of the fuze will not cause instantaneous detonation. It is noted that during 5.5 seconds, a bomb will fall approximately 145 meters. Therefore, if the plane is flying at an altitude of less than 145 meters, the fuze will be in the second position upon impact. After impact an additional eight seconds delay

is provided. This allows sufficient time for an aircraft to escape the area before the explosion of the bomb.

If the impact occurs over 5.5 seconds after launch, rotor 14 will have snapped to the third position disclosed in FIGURE 3. This movement occurs when pin 74 moves through slot 64 to allow first leg 70 to release lug 22. Rotor 14 rotates until lug 22 snaps against stop member 24. In this third position, instantaneous detonator 46 lies in line which firing pin 30. Upon impact, sensing device 48 drives firing pin 30 into detonator 46 and firing pin 32 into cup 44. An instantaneous explosion results. By the time the explosion occurs, the relatively high altitude aircraft has departed a sufficient distance from the point of impact to prevent self-inflicted damage.

The basic teachings of this invention are usable in a wide variety of specific structures. The sequence of events involved in this invention are first: releasing a rotor or other carrier member upon the occurrence of a first event, in this case launch; second: moving the carrier member to a second position in which a delay detonator lies in line with the firing pin; third: retaining the carrier member in the second position for a predetermined period of time; and fourth: moving the carrier member to a third position after the expiration of the delay period, the rotor in the third position having an instantaneous detonator in line with the firing pin.

It is possible that the rotor safety lock including the barbed feature on the firing pins and the coiled spring 40 would not be required in certain applications. In that case, only one firing pin would be needed to initiate the detonators. In other cases it might be desirable to change the time delay periods from those incorporated in the preferred embodiment. The timing periods will obviously depend upon the specific applications towards which the fuze is directed.

The preferred embodiment of this invention discloses a carrier member that lies in line with the firing pin in both the safe and the armed positions. It is apparent that the carrier member could be constructed such that it would not lie in line with the firing pin in the safe position, and would move in line only after launch.

Neither should the invention be limited to a fuze in which the second position on the rotor is occupied by a delay detonator and the third position occupied by an instantaneous detonator. The fuze could be designed such that each detonator would provide either a selected time delay or an instantaneous detonation upon impact.

It should also be possible for those skilled in the art to design a different mechanical structure to provide the delay and holding functions for the rotor. Generally speaking, a timing device is required to delay the movement of the rotor from the first to the second position and another timing device is required to hold the rotor in the second position for a predetermined period of time. In this case, both timing devices are incorporated into the same general structure. In some situations, it might be preferable to have two completely independent mechanism to perform the two tasks.

In other applications, the movement from the safe to the second position might be instantaneous in which case the first delay mechanism would not be required. The carrier member would thus snap from the safe to the second position upon launch, at which time the delay period would begin.

This invention can be incorporated into any munition fuze that utilizes a carrier member that moves from a safe position to further armed positions under the influence of a driving means such as a spiral spring. It is not necessary that the carrier member be a circular rotor as it may well be a simple slider having linear rather than rotational movement. Neither is the exact type of driving means critical. Although a spring is normally used, any driver capable of storing sufficient energy to

drive the carrier member would be considered an equivalent driving means.

From the above description it will be apparent that I have invented a new and unique dual function fuze. 5 Although the form of the invention described herein constitutes a preferred embodiment, it will be understood that changes may be made within the spirit of the invention limited only by the scope of the appended claims.

I claim as my invention:

1. An impact operated munition fuze having sequential delay and instantaneous detonating modes, comprising: a housing; a rotor mounted within said housing and rotatable about a central axis from a safe position through a delay detonating position to an instantaneous detonating position; a spring member attached to said housing and disposed adjacent said rotor; said spring member being biased away from said rotor; first and second barbed firing pins mounted on said spring member generally equidistant from said central axis; said rotor having a first annular groove formed therein in line with said firing pins in said safe position; means including impact sensing means for holding said firing pins in said first groove prior to launch of said munition to prevent rotation of said rotor, for releasing said firing pins upon launch and for driving said firing pins into said rotor upon impact; a delay detonator mounted in said rotor in line with said first firing pin in said delay detonating position; an instantaneous detonator mounted in said rotor in line with said first firing pin in said instantaneous detonating position; said rotor having a cup formed therein in line with said second firing pin in said instantaneous detonating position; driving means mounted in said housing for rotating said rotor; mechanically driven time delay means mounted in said housing and engageable with said rotor to substantially delay the rotation thereof from said safe to said delay detonating position; a movable cam follower member mounted in said housing and having first and second arms thereon; a lug member formed on said rotor adjacent said first arm with said rotor in said delay detonating position; said follower member having a first position with said first arm engaging said lug member to prevent rotation of said rotor, and a second position with said first arm out of engagement therewith; 10 said time delay means having a cam surface thereon including a first raised portion and a second slotted portion; said raised portion being positioned in line with said second arm for a period determined by the rate of movement of said time delay means to hold said follower member in said first position; said slotted portion being subsequently moved in line with said second arm to allow movement of said follower member to said second position; said rotor being completely disengaged from said cam follower member and said time delay means during the substantially instantaneous movement thereof from said delay detonating to said instantaneous detonating position; said rotor having a second annular groove formed therein between said first groove and said delay detonator; and a coiled spring mounted in said second groove to engage at least one of said barbed firing pins to lock said rotor should impact occur prior to said rotor leaving said delay detonating position.
2. An impact operated munition fuze having sequential delay and instantaneous detonating modes, comprising: a housing; a rotor mounted within said housing and rotatable about a central axis from a first position through a second position to a third position; a movable member attached to said housing and disposed adjacent said rotor; first and second barbed firing pins mounted on said movable member generally equidistant from said central axis; said rotor having a first groove formed therein in line with said firing pins in said first position; means including impact sensing means cooperating with said movable member for holding said firing pins in said first groove prior to launch of said munition to prevent rotation of

said rotor, for releasing said firing pins upon launch, and for driving said firing pins into said rotor upon impact; a delay detonator mounted in said rotor in line with said first firing pin in said second positions; an instantaneous detonator mounted in said rotor in line with said first firing pin in said third position; said rotor having a cup formed therein in line with said second firing pin in said third position; driving means mounted in said housing for rotating said rotor; mechanically driven time delay means mounted in said housing and engageable with said rotor to substantially delay the rotation thereof from said first to said second position; a cam follower member journaled for movement about a fixed pin mounted in said housing, and including first and second arms extending therefrom; a protruding stop member mounted on said rotor adjacent said first arm with said rotor in said second position; said follower member having a first position with said first arm engaging said stop member to prevent rotation of said rotor, and a second position with said first arm out of engagement therewith; said time delay means having a cam surface thereon including a first raised portion and a second slotted portion; said raised portion being positioned in line with said second arm for a period determined by the rate of movement of said time delay means to hold said follower member in said first position; said time delay means subsequently moving said slotted portion in line with said second arm to allow movement of said follower member to said second position; said rotor being completely disengaged from said cam follower member and said time delay means during the substantially instantaneous movement thereof from said second to said third position; said rotor having a second annular groove formed therein between said first groove and said delay detonator; and a coiled spring mounted in said second groove to engage at least one of said barbed firing pins to lock said rotor should impact occur prior to said rotor leaving said second position.

3. An impact operated fuze having sequential delay and instantaneous operating modes, comprising: a housing; a rotor mounted in said housing and rotatable from a safe through a delay detonating to an instantaneous detonating position; a spring member mounted in said housing adjacent said rotor; at least one barbed firing pin mounted on said spring member; said rotor having a cup formed therein adjacent said firing pin in said safe position, a delay detonator mounted adjacent said firing pin in said delay detonating position, and an instantaneous detonator mounted therein adjacent said firing pin in said instantaneous detonating position; means including impact sensing means for holding said firing pin in said cup prior to launch of said munition to prevent rotation of said rotor, for releasing said firing pin upon launch, and for driving said firing pin into said rotor upon impact; mechanically driven time delay means mounted in said housing and engageable with said rotor to substantially delay the movement thereof from said safe to said delay detonating position, and to hold said rotor in said delay detonating position for a predetermined period of time; means for driving said rotor from said delay to said instantaneous detonating position; and firing pin engaging means mounted in said rotor between said cup and said delay detonator to engage said firing pin upon impact to lock said rotor.

4. An impact operated munition fuze having both delay and instantaneous operating modes, comprising: a housing; a rotor mounted in said housing, and rotatable between a first safe position, a second delay detonating position and a third instantaneous detonating position; a flexible member, having a firing pin mounted thereon, extending from said housing adjacent said rotor; means for holding said rotor in said safe position and for releasing said rotor upon launch of said munition, driving means for rotating said rotor; impact sensing means for driving said firing pin into said rotor upon sensing an impact; a delay detonator mounted in said rotor in line

5 with said firing pin in said second position; an instantaneous detonator mounted in said rotor in line with said firing pin in said third position; and timing means mounted in said housing and engageable with said rotor for holding said rotor in said second position for a predetermined period of time.

10 5. An impact operated fuze having sequential delay and instantaneous operating modes, comprising: a housing; a carrier member mounted in said housing and movable from a safe through a delay detonating to an instantaneous detonating position; a flexible member mounted in said housing adjacent said rotor; at least one barbed firing pin mounted on said flexible member; said carrier member having a cup formed therein adjacent said firing pin in said safe position, a delay detonator mounted therein adjacent said firing pin in said delay detonating position, and an instantaneous detonator mounted therein adjacent said firing pin in said instantaneous detonating position; means including impact sensing means for holding said firing pin in said cup prior to launch of said munition to prevent movement of said carrier member, for releasing said firing pin upon launch, and for driving said firing pin into said carrier member upon impact; time delay means mounted in said housing and engageable with said carrier member to substantially delay the movement thereof from said safe to said delay detonating position, and to hold said carrier member in said delay detonating position for predetermined period of time; means for driving said carrier member from said delay to said instantaneous detonating position; and firing pin engaging means mounted in said carrier member between said cup and said delay detonator to engage said firing pin upon impact to lock said carrier member.

35 6. A munitions fuze subject to setback and impact forces, including: a resiliently mounted barbed firing pin; a movable carrier member having a first area thereon opposite said firing pin in a safe position, a second area thereon opposite said firing pin in a delay detonating position, and a third area thereon opposite said firing pin in an instantaneous detonating position; means for normally holding said carrier member in said safe position and for releasing said carrier member upon the occurrence of said setback force; means for driving said carrier member upon being released; a delay detonator mounted in said 40 carrier member at said second area; an instantaneous detonator mounted in said carrier member at said third area; means for driving said firing pin into said carrier member upon the receipt of said impact force; means engageable with said carrier member to substantially delay the movement thereof from said safe to said delay detonating position and for holding said carrier member in said delay detonating position for a timed period; and firing pin engaging means mounted in said carrier member between said first area and said second area to engage said firing pin and lock said carrier member should said impact occur prior to said carrier reaching said delay detonating position.

7. A munition fuze having both delay and instantaneous operating modes, comprising: a housing; a carrier member mounted in said housing, and movable between a first safe position, a second delay detonating position and a third instantaneous detonating position; a flexible member, having a firing pin mounted thereon, extending from said housing adjacent said carrier member; means for holding said carrier member in said safe position and for releasing said carrier member upon the occurrence of a first event; means for driving said firing pin into said carrier member upon sensing a second event; a delay detonator mounted in said carrier member in line with said firing pin in said second position; an instantaneous detonator mounted in said carrier member in line with said firing pin in said third position; means for moving said carrier member; and means for holding said carrier member in said second position for a predetermined

period of time to interrupt the movement thereof from said first to said third position.

8. A munition fuze subject to first and second events, comprising: a resiliently mounted firing pin; a movable carrier member having a first area thereon in line with said firing pin in a safe position, a second area thereon in line with said firing pin in a second position, and a third area thereon in line with said firing pin in a third position; means for normally holding said carrier member in said safe position and for releasing said carrier member upon the occurrence of said first event; means for driving said carrier member from said safe through said second to said third position upon being released; means engageable with said carrier member for holding said carrier member in said second position for a predetermined period of time; delay detonating means mounted in said second area; instantaneous detonating means mounted in said third area; and means for driving said firing pin into said carrier member upon the occurrence of said second event.

9. A munition fuze subject to first and second events, comprising: a housing; a firing pin movably mounted in said housing; a carrier member mounted in said hous-

ing having first and second detonators mounted therein; said detonators being out of line with said firing pin prior to the occurrence of said first and second events; means for aligning said first detonator with said firing pin upon the occurrence of said first event; means for thereafter holding said first detonator aligned with said firing pin for a preselected time period; means for aligning said second detonator with said firing pin upon the termination of said time period; and means for driving said firing pin into said carrier member upon the occurrence of said second event.
